To all whom it may concern:

Be it known that I, Laurence W. Brulin, a citizen of the United States and a resident of New York, in the county of New York and State of New York, have invented a new, original, and ornamental Design for a Combined Desk and Chair Unit, of which the following is a specification, reference being had to the accompanying drawing, forming a part thereof.

Figure 1 is a front perspective view of a combined desk and chair unit, showing my new design;

Figure 2 is an enlarged fragmentary sectional view of parts thereof taken on line 2-2 of Figure 1;

Figure 3 is an enlarged fragmentary sectional view of parts thereof taken on line 3-3 of Figure 1;

Figure 4 is a rear perspective view of the combined desk and chair unit;

Figure 5 is an enlarged fragmentary sectional view of parts thereof taken on line 5-5 of Figure 4; and

Figure 6 is an enlarged fragmentary sectional view of parts thereof taken on line 6-6 of Figure 4.

The dominant features of my design reside in the portions shown in full lines.

I claim:

The ornamental design for a combined desk and chair unit, substantially as shown and described.
